UNITED STATES PATENT OFFICE.

MICHAEL J. REYNOLDS, OF WEST HAVEN, CONNECTICUT, ASSIGNOR TO STRAUSE, ADLER & CO., OF NEW HAVEN, CONNECTICUT, A FIRM COMPOSED OF ISAAC M. ULLMAN, LOUIS M. ULLMAN, OF NEW HAVEN, CONNECTICUT, AND GEORGE MEYER, OF NEW YORK, N. Y.

BUTTOCKS-REDUCING CORSET.

Application filed December 13, 1924. Serial No. 755,677.

I do hereby declare the following, when taken in connection with the accompanying drawings and the characters of reference marked thereon, to be a full, clear, and exact 5 description of the same, and which said drawings constitute part of this application, and represent, in—

Fig. 1 an inside view of the corset as laid flat.

10 Fig. 2 a broken, top view of the back-section of the corset on a larger scale than Fig. 1.

My invention relates to an improvement in reducing corsets, more particularly to reducing corsets designed with particular reference to reducing the buttocks, the object being to provide a simple, convenient, comfortable and effective adjustable corset for the specific purpose designated.

20 With these ends in view, my invention consists in a reducing corset characterized by being provided with a horizontally-arranged, vertically-adjustable elastic, buttocks-reducing band located upon the inside 25 of the back of the corset-body, and adapted to have its ends connected therewith in different vertical positions.

My invention further consists in a reducing corset having certain details of construction as will be hereinafter described, and particularly pointed out in the claim.

30 In carrying out my invention, as herein shown, I employ a relatively wide, straight, buttocks-reducing band 5 of elastic material, arranged horizontally and provided at its respective ends with binding-strips 6 of any approved character, mounting hooks 7 adapted to be engaged with eyes 8 in flaps 9 flanking the non-elastic back-section 10 of

40 the corset-body, also comprising, as herein

shown, elastic hip-sections 11 and front-sections 12. The front sections 12 of the corset-body are provided with the usual applied boning strips 13 furnishing pockets for bones, and also provided upon its lower 45 edge with hose-supporters 14. The front-sections 12 are furnished with clasps 15 and corresponding studs 16, the corset being an open-front garment.

Although my invention is shown as applied to a low-down or hip-confining corset, it is not limited thereto, but may be applied to any corset-structure capable of receiving it.

I claim:—

As a new article of manufacture, an open-front closed-back reducing corset having a corset-body comprising a non-elastic back-section, elastic hip-sections having their rear edges respectively connected with the edges 55 of the back-section, non-elastic front-sections having their rear edges connected with the front edges of the respective elastic hip-sections, corset-fastening means for fastening the front edges of the non-elastic front-sections together, whereby the corset is put 60 on and off, two substantially-vertical flaps applied to the inner faces of the back-section near the respective edges thereof, and a removable horizontally-arranged elastic buttocks-reducing belt imposed upon the inner 65 face of the lower portions of the said non-elastic back-section of the corset-body and having its respective ends adjustably connected with the said flaps for its vertical 70 bodily adjustment with respect to the non-elastic back-section of the garment.

In testimony whereof, I have signed this specification.

MICHAEL J. REYNOLDS.
